SELF-LOCKING ELECTRICAL PLUG AND
SOCKET

Henry John Modrey, London, England, assignor
to Modrey Patents Corporation, Essex County,
N. J., a corporation of New Jersey

Application July 10, 1944, Serial No. 544,188

23 Claims. (Cl. 173—328)

1

This invention relates to self-locking electrical plugs and sockets wherein locked conducting engagement of the plug to the socket is effected by the insertion of the plug in the socket.

The basic principle upon which plugs and sockets with which the present invention is concerned operate is disclosed in my previous patent application U. S. Patent Office Serial No. 487,761, now Patent No. 2,423,250, issued July 1, 1947. The primary object of my present invention is to apply the said basic principle to standard systems of flat-pin outlet plugs and sockets.

A further object of my invention is to provide a plug of this flat-pin type that may readily be locked into its socket in order to prevent its being withdrawn when pull is exerted upon the plug or upon the cord or cable which is attached to the plug.

A further object is to provide an outlet plug that locks itself to its socket in the fully closed position only so that the danger of half-open plugs and sockets and the exposure of current-carrying parts is obviated.

A further object is to provide a plug and socket which, once locked by insertion, is vibration and shock proof and so lends itself to use in aircraft, railroad cars, automobiles, tanks, tractors, and other appliances which are subject to vibration.

A further object is to provide electrical outlet plugs and sockets with lower and more constant contact resistance and generally improved electrical contact qualities, by combining the self-locking mechanism with the contact parts and thus providing spring-tensioned interlocked contact, in addition to the customary frictional contact between plug and socket contacts.

A further object is to provide a plug which upon insertion into its socket, is capable of supporting the weight of electrical appliances such as lighting fixtures or portable tools.

A further object is to provide a plug and socket suitable for overhead wiring, viz., for the provision of semi-permanent electrical connections between electrical appliances and a plurality of socket outlets mounted overhead or carried on bus bars or conduit tubes.

A further object is to provide a plug suited for fire alarm or burglar alarm installations that, once inserted cannot be removed from its socket unless access is had to the underside or inside of the socket.

A still further important object of my invention is to provide for interchangeability between American or other standard systems of electrical outlet plugs and sockets, and the system of 55 self-locking plugs and sockets according to my

2

invention, in that socket outlets according to my invention will receive such standard plugs, and plugs according to my invention will fit into such standard socket outlets. It is of course understood that self-locking action will result only from the conjoint use of plugs and sockets according to my invention.

The invention will be clearly understood on reference to the accompanying drawings which 10 form part of the specification:

Figure 1 is a perspective view of the plug contact blade with the locking mechanism attached;

Figure 2 is a perspective view of the socket contact containing the said opening or slot;

15 Figure 3 is a perspective view of the two aforementioned components in locked conducting engagement;

Figures 4, 5, 6, 7 are sectional views of the contact blade, the locking mechanism, and part of 20 the socket contact, in progressive stages of locking engagement;

Figures 8, 9 are part-sectional views of a plastic twin-pole plug;

Figures 10, 11 are part-sectional views of a 25 twin-pole plug made from rubber;

Figures 12, 13 show a plan view and a sectional view respectively of a twin-pole socket;

Figure 14 is a part-sectional view of a twin-pole plug of a spring-less type, made from rubber;

30 Figures 15a and 15b show details of the locking mechanism employed in the plug shown in Figure 14;

Figure 16 is a perspective view of a five-pole 35 plug;

Figure 17 is a plan view of the corresponding socket outlet;

Figure 18 is a perspective view of a circular 40 five-pole plug;

Figure 19 is a plan view of the corresponding socket outlet;

Figure 19a is an elevational side view of a connected plug and socket according to Figs. 18 and 45 19 respectively.

Figures 20a and 20b show details of a compensating socket contact, used as a centre contact in the socket outlet shown in Figure 19;

Figure 21 is a part-sectional view of an 50 appliances plug;

Figure 22 is a sectional view of the corresponding line socket.

Referring to these drawings wherein, like or corresponding parts have been as far as possible designated by identical reference numbers—

The plug contact blade shown in Figure 1 consists of a stem 1 terminating in an enlarged blade

contact 2. The locking slide 4 is held in slidable engagement with the stem 1 by the slide ring 5, and is spring influenced axially between the blade contact by a spring 6 which bears against the head 4a of the locking slide 4, and against the corner 1a of the stem 1 respectively. 3 indicates a hole to which a conducting wire or a terminal screw may be affixed.

Referring to Figure 2, which illustrates the socket contact, the length of the rectangular slot 8 in the top part 7 of the socket contact corresponds to the width of the blade contact 2, at its widest part. The cross sectional width of the slot 8 may conveniently exceed that of the thickness of the blade, so as to permit access to blades of different thickness, according to their respective current carrying capacities. The tongue 10 presses against the back 9 of the contact and is located between stops 11 and 12.

Figure 3 shows the plug and socket in operative relation with the plug inserted and in locked conducting engagement with the socket contact.

Figures 4 to 7 show, in successive stages, the operation of the mechanism during insertion and removal. The following description in general applies to the mechanism of all the various form of plugs and socket described hereinafter.

Blade 2 is entered into the slot 8, Figure 4 showing the position immediately before the entry. Towards the end of its travel, the locking slide 4 bears against the surface 7 of the socket contact. Slot 8 being substantially filled as to its larger dimension by blade 2, the slide 4 is thus pushed backwards axially, compressing the spring 6, as shown in Figure 5. As soon as the slope 2a which connects the stem 1 with the enlarged blade 2, is reached, blade 2 is displaced sideways so that the spring-influenced locking slide 4 snaps into the slot 8, as shown in Figures 6 and 3.

The stem 1 together with the locking slide 4 now fills substantially the slot 8 and, as a result, the enlarged blade 2 underlies the underside of the slot 8 by the displacement width of the locking slide 4. It will be obvious that pull at the stem 1 cannot remove blade 2 as the joint width of the parts now situated below slot 8, considerably exceeds the length of the slot, and in consequence the locking action of the mechanism is mechanically positive, and not frictional or dependent on spring pressure. Electrical contact is established by the blade 2 entering in between back plate 9 and tongue 10 of the socket contact, and is supplemented by the locking mechanism engaging the socket contact under spring influence.

Figure 7 shows the unlocking action. The locking slide 4 has been lifted clear of slot 8, against the pressure of spring 6. Once this position of the locking slide 4 relative to the slot 8 is reached, blade 2 is at liberty to slide sideways under the cam action of the slope 2a, and can thereafter be withdrawn through the slot 8.

To sum up, the blade is locked automatically by the inserting push, and removed automatically by pull applied to the locking slide. The various forms of plugs and sockets hereafter described, embody various means of applying these two actions.

The whole of the foregoing description must be understood as referring to relative movements of the various parts, as the locking principle according to my invention applies also to a mechanical reversal of the mechanism or the order

of operation. For instance, Figures 21 and 22 show a plug and socket respectively in which self-locking is effected not by insertion of the plug, but by movement of the socket relative to the stationary plug.

Figures 8, 9, 10 and 11 show twin-pole plugs embodying the invention. In Figures 8 and 9 two blades and locking slides are contained in a housing of plastic or the like insulating material. 10 This housing 18 has in its bottom two slots 19 which serve to replace the functions of the missing slide or collar 5, by holding the locking slides 4 and the stems 1 in slidable engagement. The top portion of the plug consists of two parts 14 and 15 which are connected by a holding screw 16, once the cord or cable 17 has been wired to the terminal screws 3a. Parts 14 and 15 conjointly are so shaped as to slide inside the bore of the housing 18. The inside of the two parts 15 14 and 15 contains recesses such as shown in 14c which ensure that both parts are firmly joined to the terminal portion of both stems 1, once the connecting screw 16 has been fastened.

Figures 12 and 13 show the corresponding socket outlet which contains two socket contacts as shown in Figure 2. The lugs 1a and 1b shown in Figures 2 and 13, serve to affix the socket contacts to the insulating socket top plate which may be a plastic moulding. The top plate 24 has a slightly recessed portion 25, corresponding in shape to that of the bottom of a plug. Two slots 26 disclose the locking slots 8 in the two socket contacts. Affixed to the socket contacts are two terminal screws 27 and 28.

35 The socket outlet as described is identical for all twin-pole plugs described herein. It will be obvious that the outlet will also co-operate in the customary manner with any standard twin-pole plug, the blades entering through the clearance slots 26 and the slots 8 in between the socket contacts where they are held between the back plates 9 and the tongues 10. It will further be obvious that the tongue 10 is not essential for the functioning of the socket contact, the provision of an appropriately shaped slot 8, in conjunction with a socket contact of suitable shape, being all that is necessary to establish good electrical connection.

50 If any twin-pole plug according to my invention is inserted into the socket outlet shown in Figures 12 and 13, by pressing on the top part 14-15 of the plug, the locking mechanism on both blades will engage in its corresponding slot 8, as previously described with reference to Figures 4-6. Subsequent pull at the cord or cable 55 cannot dislodge the plug, short of shearing blade 2 through a slot of considerably smaller cross section.

The plug can only be removed by pull at the bottom housing 18, when the locking slide 4 is lifted clear off the slot 8, as shown and described with reference to Figure 7. Parts 18 and 14-15 slide freely inside each other, and it will be obvious that pull at the cord or cable 17 is not transmitted to the housing 18.

70 The amount of telescoping movement required for the operation of the locking mechanism, is indicated in Figures 8 and 9 by means of dotted lines. For convenience of operation, it is desirable to keep this "operating stroke" as small as possible. The operative position of the locking mechanism is reached when the slope 2a is projected slightly beyond the tip of the locking slide 75 4, and the required operating stroke therefore de-

pends upon the protruding length of locking slide 4.

On the other hand, with a short locking slide 4, there is a certain danger that a rocking or sideways motion applied to the inserted plug may project the end of locking slide 4 longitudinally out of its locking slot 8, in which case the locking mechanism would disengage. It is therefore essential to hold the plug forcibly in an upright position, relative to its socket.

To a certain extent, the plug is so steadied by the shaped recess 25 in socket plate 24, as shown in Fig. 12. The depth of this recess however should not exceed the protruding length of the locking slide 4, in view of the slight zigzag movement occurring during the insertion of the plug when blades 2 jump via their slopes 2a from an axially symmetrical position into locked position. This limitation as to depth, limits the usefulness of the said recess 25 for steadyng purposes.

It is not convenient to use for such steadyng purposes the means customarily applied to standard plugs and sockets, viz., provision of indentions or holes in the blades, and of corresponding raised portions in the socket contacts. It is evident from Figs. 4 to 6 that, owing to the sideways displacement occurring during the locking motion, the blade comes to rest in a position which is unsymmetrical in relation to the true axis of the socket contact. If therefore the described customary means for steadyng the plug blades were employed, the said raised portions would have to be in unsymmetrical positions on the socket contacts, and as a result the plug could only be inserted in one given position. As indiscriminate insertion is the more common requirement for outlet plugs, positive steadyng of the plugs against the socket is achieved by the following means:

At the side of the contact back plate 9, the two bent lugs 11 and 12 are provided, as shown in Figs. 2 and 3. The back plate 9 is of such width that the side of blade 2, after insertion, is flush with one side of the back plate 9, whichever way the blade is inserted. In Figure 3, lug 11 therefore makes it impossible for blade 2 to move sideways on this side.

By arranging two contacts within one socket outlet to be fixed in opposite directions, as shown in Fig. 13, both lugs 11 and 12 on opposite sides of the two back plates 9 in the two contacts, come into play and conjointly prevent any movement of the blades 2. These lugs afford a positive holding device, irrespective of the shape of the plug housing, and independent of the position of the plug.

It will be obvious that a plug according to my invention may be used in conjunction with an appropriate standard socket. The blades 2 will enter a standard socket contact, and with most types of standard socket, the relative movement between blades and locking slides will assist in inserting the plug to its full depth. In the absence of locking slots in the socket outlet, the locking mechanism of the plug cannot, of course, become operative.

Whilst Figs. 8 and 9 show a plug made from plastic or the like insulating material, Figs. 10 and 11 show another twin-pole plug for cooperation with the socket shown in Figs. 12 and 13, 70 made from rubber or the like elastic material.

As described with reference to Figs. 8 and 9, the plastic plug requires for locking and unlock- 75 ing a slight telescoping movement between its top and bottom portions. In the rubber plug accord-

ing to Figs. 10 and 11, the necessity for providing separate telescoping parts has been eliminated, by providing an elastic housing capable of longitudinal compression which affords the required longitudinal movement.

Two blades with attached locking mechanism are contained in the rubber housing 28-21, which is shown to consist of two symmetrical halves to be joined together after the cord or cable 17 has been connected to the terminal screws 3a. The top parts of both 28 and 21 contain shaped recesses 28a which insure that once the two halves 28 and 21 have been joined together, the said top parts conjointly are firmly connected to the terminal portions of both blade stems 1. The slide rings 5 are embedded and held in the thick bottom portion of the joined rubber housing.

If the plug is inserted into a socket as shown in Figs. 12 and 13, and for this purpose is pushed in by the grooved top part 22 (marked "In"), the plug which rests on the socket top plate will be compressed as indicated by the dotted lines, until operative position of blades 2 relative to the locking slides 4 (likewise indicated by dotted lines) is reached, when the locking mechanism engages. The plug is again impervious to pull at the cable, but may be removed by pull at the grooved bottom part 23 (marked "Out"), or alternatively by holding the plug at 23 and depressing top part 22. Either action will bring the locking mechanism into operative position as shown in Fig. 7. Internal rubber buffers may be employed to stiffen the housing and to prevent undue compression of the housing during insertion or removal.

Fig. 14 shows a simplified type of twin-pole plug made from rubber or other elastic material, in which the inherent elasticity of the housing material is utilised to replace the operating spring 6. The plug shown by way of example is of the type wherein the cover of the appliances cord or cable is moulded integrally with the plug body.

The spring 6 operated so as to push the locking slide 4 and the slide ring 5 constantly towards blade 2. This action is replaced by the inherent elasticity of the rubber housing 28 and 31, which may be increased by an appropriate arrangement of internal ribs 38a, b, c, d which favours easy compression of the housing, but at the same time limits the stroke.

However, another function of spring 6 was to hold locking slide 4 in its position inside the slide ring 5, by means of pressure on the slide head 4a. In the absence of a spring this action must be compensated by fastening locking slide 4 permanently to slide ring 5, for example by means of a pin or rivet 32 as shown in Fig. 15. The locking slide 4 then participates in the spring tension imparted to slide ring 5 by the elastic housing, and the plug functions and is inserted and removed as described with reference to Figs. 10 and 11.

Apart from the obvious simplification in design, springless elastic plugs according to my invention offer electrical advantages for use in ultra-high frequency circuits in which operating spring 6, although small and short-circuited, may conceivably set up disturbances. For the identical reason, springless plugs offer electrical advantages for use in co-axial connectors.

Fig. 16 shows a multi-pole plug containing by way of example five flat-pin contacts in line. In a plug of this description it is not necessary for effective locking, to attach a locking mechanism to each contact blade, unless of course this is desirable on electrical grounds. On the plug

shown in Fig. 16, locking slides 4 have been added only to the two end blades, whilst the three centre blades 35a, b, c are without such locking mechanism. All blades are anchored in the top part 34 of the plug which is capable of telescoping movement inside the housing 33, as described with reference to the twin-pole plug shown in Figs. 8 and 9. Access to the terminals may be had by removing the top plate 36 which also releases the cord or cable from the cable gland 37. The plug is inserted and locked by pressure upon its top 34-36, and is removed by pull at the housing 33, or by compressing the top 34-36 relative to the housing 33.

It is not advantageous to fasten the non-locking blades 35a, b, c to the housing 33, as in this case the telescoping movement between the two plug parts 33 and 34 would be taken up by the wires in the cord or cable 17 which are firmly clamped into the cable gland 37, but would have to follow the terminals attached to 35a, b, c on their downward move, with the result that breakages are likely to occur after some time. It is more advantageous to have stationary terminals and to let the auxiliary blades participate in the slight movement imparted to the locking blades during locking and unlocking.

Fig. 17 shows the arrangement of the corresponding socket which is equivalent, except for the number of contacts provided, to the socket shown in Figs. 12 and 13, although the three centre contacts may be constructed without the locking slots.

However, in the construction of the three centre socket contacts or of the corresponding blades 35a, b, c, the sideways displacement movement occurring during insertion of the plug must be taken into account. In the instance of Fig. 16, narrower contact blades have been provided so as to prevent jamming whilst this zigzag movement occurs.

Fig. 18 shows a circular 5-pole plug in which only the centre blade 2 carries a locking slide 4. Fig. 19 shows the arrangement of the corresponding socket. In this construction, the zigzag or displacement movement occurring at the centre blade 2 during the locking motion (shown in Figs. 5 and 6) would prima facie make operation impossible, as the permissible motion of the plug is limited by the four non-locking blades 35a, b, c, d which once inserted permit only of a straight rectilinear movement. Moreover, plugs of this kind are usually inserted into their sockets to a considerable depth, and are thus further guided by the socket opening which permits only of a straight downwards motion. It is impossible, in this instance, to apply the means indicated in Figs. 16 and 17, viz., narrower non-locking blades, as all blade-receiving slots point into different directions whilst the displacement movement occurs in the lengthwise direction of the central or locking slot 48.

In a plug of this type (or in other cases where the displacement movement interferes with the proposed operation of the plug), the displacement movement must be compensated. The socket contact shown in Figs. 20a and 20b permits of such compensation. The locking plate 47 is slidably affixed between the insulating socket cover 45 and the socket contact 49. The amount of slide action is limited to the required displacement movement on either side (viz., the width of the locking slide employed).

The blade 2 is inserted into the clearance slot 46 in the socket cover 45, enters the locking slot 48 in the slide 47 (thereby centering the slide),

and through the clearance slot 50 enters in between the contact tongues 49a and b. Once blade 2 has reached the position shown in Fig. 5 (the locking slide 47 being substituted for the top part 7 shown in Fig. 5), the locking slide 4 enters the locking slot 48, at the same time displacing the movable locking slide 47 sideways, as required.

This displacement compensation inside the socket contact enables plugs and sockets to be joined and parted by means of a straight rectilinear movement, so that the relative angular position of non-locking blades as shown in Fig. 18, as well as their width does not interfere with the proper functioning of the connector. It will be obvious that if displacement is compensated as aforesaid, pin type auxiliary plug contacts may be employed, cooperating with tubular contacts within the socket.

The plug shown in Fig. 18 corresponds to the one shown in Fig. 16, in that both blade 2 and the auxiliary or non-locking blades are anchored to the telescoping top part 41, whilst access to all terminals is had by unscrewing part 42. The plug is inserted by pushing it into the socket by pressure on part 42, and is removed by pulling at the knurled portion of the housing 40 which again serves to lift the locking slide 4 until the plug disengages.

In view of the foregoing, the construction and function of the socket according to Fig. 19 will be self-explanatory. Socket contacts 48a, b, c, d may obviously be standard socket contacts. As a result of displacement compensation, the socket cover 45 may be located considerably below the flange 43 of the socket, as long as the knurled portion of the plug body 40 protrudes sufficiently to afford a grip.

If the insertion depth is increased to such an extent that no part of housing 40 protrudes, the plug may be locked in its socket as described, but cannot be removed or withdrawn without dismantling the socket, or lifting the locking slide 4 from the underside of the socket by means of an instrument. A plug embodying this feature may be used for purposes where it is undesirable to have the plug removed once it has been inserted, such as, for example, in burglar or fire alarm installations.

Fig. 19a shows the plug of Fig. 18 applied to the socket of Fig. 19. As will be noted, cover plate 45 of the socket is recessed to form a cup-shaped portion 43a which receives plug body 40. As will be apparent, plug body 40 is not accessible after being pressed home. As a result, the connector elements can not be separated without access to the underside of the socket or a special instrument. The insertion of the plug body into a recess of the socket has also the advantage that the connector presents a continuous surface of insulation material, thereby avoiding the danger of short circuits or shocks. For the latter purpose, of course, it will not be necessary to recess the socket so deeply that the plug body is entirely concealed.

Fig. 21 shows an appliances plug according to my invention, viz., a plug for incorporation with domestic and like electrical appliances, to be connected to a current-carrying socket which is affixed to a cord or wire, as shown in Fig. 22.

The top or terminal part of the two blade stems 1 is affixed to an insulating housing 51, through the bottom of which the terminal screws 3a protrude, for connecting inside the electrical appliance. The flange 51a is affixed to the said ap-

pliance, and the telescoping inner housing 52 which carries two slide rings 5 guiding blades 2 and locking slides 4, protrudes slightly from the flange 51a.

The line socket shown in Fig. 22 may be made from plastic, rubber or other insulating material, and embodies two of the socket contacts shown in Fig. 2, duly positioned and separated by recesses and a central wedge or separator 54a in the housing 54. Access to the locking slots 8 is had through the clearance slots 55 in the housing.

If the socket with its two locking slots 8 is pushed over the two plug blades 2, the locking slides 4 are lifted and the locking mechanism functions as shown in Figs. 5 and 6, but with the distinction that in this instance the blades are held stationary whilst the locking slots 8 are moved upwards, until both locking slides are free to snap into their locking slots 8.

To remove the line socket, it is again necessary to lift the locking slides 4 clear off their respective locking slots 8. The required relative movement between the two blades 2 and their locking slides 4 in this application of my invention, is effected by depressing the knurled rim 53 of the inner housing 52 (as shown in dotted lines) until the locking slides 4 are free, when the line socket can be withdrawn.

The description of various electrical outlet plugs and sockets according to my invention, shows that the basic flat-pin locking mechanism described therein, may be incorporated within various forms of electrical outlet plugs and sockets. The displacement-compensation socket contact shown in Figs. 20a and 20b, serves to remove constructional limitations originally inherent in the locking mechanism. The range of connectors described is by way of example only, whilst it will be obvious that various permutations or adaptations of the basic self locking mechanism as applied to plugs and sockets, may be constructed without departing from my invention.

It will be obvious that the self-locking plugs and sockets according to my invention constitute a complete system, ranging from single pole plugs to multi-pole plugs of various forms and comprising all customary accessories. It is also to be understood that plugs and sockets according to this system may be constructed so as to be interchangeable with those of other standard flat-pin systems.

All or any of the plugs and sockets according to this system show the following characteristics:

A plug, once inserted, is impervious to accidental or deliberate cable pull, and to the effects of severe shock or vibration. The locking strength is independent of the operating spring employed, but is equivalent to the shearing strength of the contact blade in its socket hole. For this reason, the plug is capable of supporting considerable weight such as lighting fixtures or portable tools, and may therefore conveniently be employed for overhead or bus-bar wiring in factories, or for the installation of quickly removable lighting fixtures such as fluorescent lamps, inspection lamps, lighting fixtures in showrooms, or the like.

Moreover, the contact parts themselves in plug and socket respectively, form the locking mechanism. Once the plug has been inserted, the customary friction contact between blade and socket contact is established, but in addition hereto contact blade and socket contact are mechanically interlocked and under constant spring ten-

sion. This supplementary interlocking contact results in a higher degree of contact quality and electrical efficiency, by reducing the contact resistance, and generally relieving the dependence on the springiness of the socket tongues which tends to decrease with continued use. The applied spring-tension makes this interlocking electrical contact eminently suitable to withstand vibration and shock, without change in contact resistance.

Lastly, electrical plug and socket outlets according to my invention lock only when inserted to full depth. That is to say, once inserted, there cannot be any gap between plug and socket in which current-carrying parts are exposed, as is the case with half-opened standard plugs and sockets. This safety feature can be further enhanced by providing an operating spring which it is impossible for a child to compress so as to unlock the plug, whilst it can be easily handled by an adult person.

It will be clear from the foregoing that, broadly stated, my invention involves the provision of a locking mechanism affixed to or acting in association with the contact blade or blades of a flat-pin plug. If the locking blade—which may or may not be a current carrying element—is inserted in an opening or slot, the said locking mechanism becomes operative during the process of insertion. During the final movement of insertion, a recessed portion of the blade enters the slot, and this reduced width of the blade allows the spring-tensioned locking slide to snap into the said slot, alongside the blade. The non-recessed wider front part of the blade now overhangs the slot and remains locked therein, until the locking slide is lifted or withdrawn from the slot.

What I claim and desire to secure by Letters Patent is:

1. In an electrical plug connector a contact socket including a locking plate having a slot therein, a cooperating locking device comprising a flat blade having its forward end of width designed for insertion through said slot, said blade being cut away on one side to form a stem of lesser width than that of the forward end of the blade and thus to provide a locking shoulder at the top of said forward end, a locking slide slidable within limits along the uncut edge of the blade, the effective part of said locking slide being of a width substantially equal to the width of the portions cut-away from the opposite edge, means to hold the locking slide in slidable engagement with the edge of the blade and to impose a limit on its forward movement, and yieldable means tending to maintain said locking slide in its forward position.

2. In an electrical plug a locking device according to claim 1, wherein the means for holding the locking slide in slidable engagement with the blade and limiting its forward movement is constituted by a slotted guide.

3. In an electrical plug a locking device according to claim 1, wherein the means for holding the locking slide in slidable engagement with the blade and limiting its forward movement is constituted by a slotted guide positively secured in the bottom of a casing containing the stem of the blade.

4. In an electrical plug a locking device according to claim 1, wherein the means for holding the locking slide in slidable engagement with the blade and limiting its forward movement is constituted by a slotted guide positively secured in

11

the bottom of a casing containing the stem of the blade, and the locking slide is positively connected to the slotted guide.

5. In an electrical plug a locking device according to claim 1, wherein the means for holding the locking slide in slidable engagement with the blade and limiting its forward movement is constituted by the slotted end of a casing housing the stem of the blade.

6. In an electrical plug connector a contact socket including a locking plate having a slot therein, a cooperating locking device comprising a flat blade having its forward end of width designed for insertion through said slot, said blade being cut away on one side to form a stem of lesser width than that of the forward end of the blade and thus to provide a locking shoulder at the top of said forward end, a locking slide slidably within limits along the uncut edge of the blade of a width substantially equal to the width of the portion cut away from the opposite edge, a guide beyond which the forward wider end of the blade projects and through which the forward effective part of said locking slide passes, and yieldable means acting on the locking slide, whereby on passage of the wider forward part of the blade into and through the slot in the locking plate of the socket the locking slide is moved relatively to the blade against the yieldable means until the wider forward part of the blade has passed through the slot in the locking plate whereupon the forward end of the locking slide is freed for projection into the slot in the socket locking plate alongside the narrower stem of the blade, and thereby displaces the blade sideways to secure the locking shoulder in locked engagement beneath the underside of the locking plate.

7. An electrical plug comprising a flat blade having its contact making forward end of normal width for insertion into co-operating engagement with a flat-pin socket contact said blade being cut away on one side to form a stem of lesser width than that of the contact making forward end and thus to provide a locking shoulder at the top of said contact making forward end, a locking slide slidably within limits along the uncut edge of the blade of a width equal to the width of the portion cut away from the opposite edge, a guide beyond which the forward contact making end of the head projects and through which the forward part of said locking slide passes, yieldable means acting on the locking slide, and means to limit the forward movement of the locking slide under the influence of the yieldable means, whereby on passage of the wider contact making part of the blade into and through a slot in the socket plate the locking slide is moved relatively to the blade against the yieldable means until the wider contact making part of the blade has passed through the slot in the socket plate whereupon the forward end of the locking slide is freed for projection into the slot in the socket alongside the narrower stem of the blade, to displace the blade sideways and thus secure the locking shoulder in locking position beneath the underside of the socket plate.

8. An electrical plug comprising a flat blade having its contact making forward end of normal width for insertion into co-operating engagement with a flat-pin socket contact said blade being cut away on one side to form a stem of lesser width than that of the contact making forward end and thus to provide a locking shoulder at the top of said contact making forward end, a headed locking slide slidably within limits

12

along the uncut edge of the blade of a width equal to the width of the portion cut away from the opposite edge, a guide beyond which the forward contact making end of the head projects and through which the part of said locking slide beyond its head passes, and spring means acting on the head of the locking slide, whereby on passage of the wider contact making part of the blade into and through a slot in the socket plate the locking slide is moved relatively to the blade against the spring means until the wider contact making part of the blade has passed through the slot in the socket plate whereupon the forward end of the locking slide is freed for projection into the slot in the socket alongside the narrower stem of the blade, thereby to displace the blade sideways and thus secure the locking shoulder in locked engagement beneath the underside of the socket plate.

20 9. An electrical plug comprising a terminal block, a flat blade connected to said block and having its contact making forward end of normal width for insertion through the slot of a co-operating flat-pin contact socket, said blade being cut away on one side to form a stem of lesser width than that of the contact making forward end and thus to provide a locking shoulder at the top of said contact making forward end, a housing through which the stem passes with relation to which the terminal block can telescope, a headed locking slide slidably along the uncut edge of the blade of a width substantially equal to the width of the portion cut away from the opposite edge, a guide slot in the lower end of the housing beyond which the forward contact making end of the head projects and through which the operative part of said locking slide passes, the part of the bottom end of the housing bordering the slot therein co-operating with the head of the locking slide to limit both the forward movement of said locking slide and the rearward movement of the blade, and a spring surrounding the stem of the blade and acting on the locking slide, whereby on passage of the wider contact making part of the blade into and through the slot in the socket plate the locking slide is moved relatively to the blade against the influence of the spring until the wider contact making part of the blade has passed through the slot in the socket plate whereupon the forward end of the locking slide on projection into the slot in the socket alongside the narrower stem part of the blade displaces the blade sideways and thus secures the locking shoulder in locked engagement beneath the underside of the socket plate.

40 10. An electrical plug according to claim 8, wherein a pair of the contact making blades and locking mechanisms are arranged side by side in a common housing to form a twin pole plug.

60 11. An electrical plug connector according to claim 1, wherein the socket is provided with a cup-shaped insulation portion, and wherein the plug is adapted to lock in the socket only when the contact making parts of the plug have been inserted sufficiently far into the cup-shaped portion of the co-operating socket that they are enclosed and shielded against outside contact by the insulation of said portion.

65 12. An electrical plug according to claim 7, wherein the yieldable means is constituted by the resilience of the housing.

70 13. An electrical plug having a locking mechanism according to claim 1 and additional current carrying blades.

14. An electrical plug having locking mechanism according to claim 1, wherein a locking blade and its locking mechanism is situated centrally of the plug and current carrying contact blades are arranged around it.

15. An electrical plug having locking mechanism according to claim 1, wherein a locking blade and its associated locking mechanism is situated centrally of the plug and current carrying contact blades are arranged around it, and the socket has a slidable slotted plate whose movement compensates for the displacement movement of said locking blade.

16. An electrical plug having locking mechanism according to claim 1 wherein the flat blade carries current and a socket contact element comprises a one-piece bent up strip metal member having a back plate with which one face of the current carrying blade of the cooperating flat pin contact plug makes contact, a resilient tongue with which the other face of the current carrying blade makes contact, and a slotted socket plate joining the back plate to the tongue.

17. An electrical plug having locking mechanism according to claim 1 wherein the flat blade carries current and a socket contact element comprises a one piece bent up strip metal member having a back plate to which electrical connection is made with which one face of the current carrying blade of the flat-pin contact plug makes contact, a resilient tongue diverging at its upper end from said back plate and resiliently connected thereto by a bridge forming the socket plate, a slot in the socket plate designed to receive the current carrying blade of the contact plug and permit it to be inserted and held between the back plate and the free end of the tongue, and bent over lugs at the sides of the back plate to restrain lateral movement of the tongue relative to the back plate.

18. An electrical plug connector having a locking mechanism according to claim 1 wherein the flat blade is arranged to carry current, and a socket having flat contact elements with which the blade of the flat-pin plug can make contact, and a slotted locking plate so located that when the plug is inserted the contact blade of the plug passes through the slot prior to its reaching the contact element of the socket, whereby when the plug is fully inserted the locking shoulder of the displaced contact blade becomes locked beneath the locking plate.

19. An electrical plug connector having a locking mechanism according to claim 1, in combination with a socket having its locking plate located at such a depth that when the plug has been inserted into locked engagement with the socket its removal can only be effected by destruction or the aid of special tools.

20. An electrical plug connector comprising a plug member and a socket member including a locking plate having a slot therein, said plug member including a flat blade having a forward contact end designed for insertion into said slot, said blade being cut away on one side to form a stem of lesser width than that of said forward end and to provide a locking shoulder at the top of said forward end, a locking slide slidable within limits along the uncut edge of the blade and a width substantially equal to the width of the portion cut away from the opposite edge, a housing made of flexible material within which housing the blade and the locking slide are disposed, said housing

supporting the stem and including a guide slot beyond which the forward wider end of the blade projects and through which the forward effective part of the locking blade passes, whereby, on passage of the wider forward part of the blade into and through the slot in said locking plate of the socket member, the locking slide is moved relatively to the blade in response to a compression of the flexible housing into the direction of the stem axis until the wider forward part of the blade is passed through the slot in the locking plate whereupon the forward end of the locking slide is freed for projection into the slot in the socket locking plate alongside the narrower stem of the blade, thereby displacing the blade sideways to secure the locking shoulder in locked engagement with the underside of the locking plate.

21. An electrical plug connector comprising a plug member and a socket member including a locking plate having a slot therein, said plug member including a flat blade having a forward contact end designed for insertion into said slot, said blade being cut away on one side to form a stem of lesser width than that of said forward end and to provide a locking shoulder at the top of said forward end, a locking slide slidable within limits along the uncut edge of the blade and a width substantially equal to the width of the portion cut away from the opposite edge, a housing made of flexible material within which housing the blade and the locking slide are disposed, said housing supporting the stem and including a guide slot beyond which the forward wider end of the blade projects and through which the forward effective part of the locking blade passes, and spring means surrounding the stem and acting on the locking slide, whereby, on passage of the wider forward part of the blade into and through the slot in said locking plate of the socket member, the locking slide is moved relatively to the blade in response to a compression of the spring means and of the flexible housing into the direction of the stem axis until the wider forward part of the blade is passed through the slot in the locking plate whereupon the forward end of the locking slide is freed for projection into the slot in the socket locking plate alongside the narrower stem of the blade, thereby displacing the blade sideways to secure the locking shoulder in locked engagement with the underside of the locking plate.

22. In an electrical plug connector a contact socket including a contact plate having an opening therein, a laterally slidable locking plate having a slot therein elongated in the direction of the lateral locking plate movement and positioned to be in registry with said opening, the longitudinal length of said slot being shorter than the length of said opening in the direction of the lateral locking plate movement, and a co-operating locking device comprising a flat blade having at its forward end a width designed for insertion through said slot, said blade being cut away on one side to form a stem of lesser width than that of the forward end of the blade and thus to provide a locking shoulder at the top of said forward end, a locking slide slidable within limits along the uncut edge of the blade, the effective part of said locking slide being of a width substantially equal to the width of the portions cut-away from the opposite edge, means to hold the locking slide in slidable engagement with the edge of the blade and to impose a limit on its forward movement, and yieldable means tending to maintain said locking slide in its forward position.

15

23. An electrical plug connector according to claim 1, in combination with a plurality of flat contact blades arranged to carry current supported on the plug, and corresponding receiving contact elements provided on the socket.

HENRY JOHN MODREY.
